UNITED STATES PATENT OFFICE.

EMIL G. SAUER, OF BROOKLYN, NEW YORK, ASSIGNOR TO THE LOWELL MANUFACTURING COMPANY, OF BOSTON, MASSACHUSETTS.

DESIGN FOR CARPET.

SPECIFICATION forming part of Design No. 23,693, dated October 16, 1894.

Application filed September 17, 1894. Serial No. 523,285. Term of patent 3½ years.

To all whom it may concern:

Be it known that I, EMIL G. SAUER, a citizen of the United States, residing at Brooklyn, in the county of Kings and State of New York, have invented and produced a new and original Design for Carpet, of which the following is a specification, reference being had to the accompanying drawing, making a part of the same, and is sufficient to enable others skilled in the art to make and use my invention.

That part of the drawing representing the border A, at B, B', only one half of the figure is shown. The parts not shown, are substantially like the parts that are shown.

What I claim as new, and desire to secure by Letters Patent, is—

1. In a design for a carpet, the body D, substantially as shown.
2. In a design for a carpet, the border A substantially as shown.
3. The design for a carpet, consisting of the body D and border A substantially as shown.

EMIL G. SAUER.
